ATTORNEY

UNITED STATES PATENT OFFICE

JESSE OPPENHEIM, OF NEW YORK, N. Y.

HAIRDRESSING ACCESSORY

Application filed December 7, 1928. Serial No. 324,448.

This invention relates to hair dressing accessories.

An object of this invention is to provide an appliance of the character described having means for positively keeping the side hair off the face to effect one of the well known styles in women's coiffures.

A further object is to provide a device of the character described having means particularly adapted for giving the appearance of long hair to a coiffure wherein the hair is drawn off the face and tightly clamped at the back of the head.

A further object of this invention is to provide a unitary device of the character described having the functions of a barrette for the hair in the back of the head and side combs for the hair at the sides.

Another object of this invention is to provide a device of the character described which shall be neat, compact and rugged in construction, relatively inexpensive to manufacture, convenient to apply and remove, and yet practical and efficient to a high degree.

Other objects of this invention will in part be obvious and in part hereinafter pointed out.

The invention accordingly consists in the features of construction, combinations of elements and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a profile view of a woman's coiffure showing a device embodying the invention in use.

Fig. 2 is a rear elevational view of the device.

Fig. 3 is a fragmentary top plan view of the comb band and attached hair piece.

Fig. 4 is a front elevational view of the structure shown in Fig. 3.

Fig. 5 is a fragmentary front elevational view of the comb band and one side comb showing an adjusted position of the comb.

Fig. 6 is a cross-sectional view taken on line 6—6 of Fig. 2.

Fig. 7 is a fragmentary front elevational view of a modified construction.

Referring in detail to the drawing, 10 designates a hair dressing appliance embodying the invention in the form of a combined 55 barrette and hair piece for women's coiffure. Said appliance 10 comprises a hair clamping or barrette portion 11 mounting a hair piece 12.

Said hair clamping device or barrette 11 60 comprises a curved band 13 of celluloid, horn, or the like material, adapted to fit a portion 65 of the back of the user's neck and interconnecting a pair of hair clamping members 14.

Said members 14 are pivoted as by pins or 70 rivets 15 adjacent the end portions 16 of said band 13, at the inner surface 17 thereof. Said members 14 conform generally to the curvature of said inner surface 17 and each comprises a frame member 18 and small comb 19.

Said frame member 18 is substantially rectangular in shape and comprises a top portion 20, a bottom portion 21, and side portions 22. The top portion 20 is fixed to the top portion 23 of the comb 19 in any suitable manner, 75 the teeth 24 of the latter, however, being slightly spaced from the sides and bottom portion of said frame member, as clearly shown in Fig. 6 of the drawing. In mounting a hair clamping member 14 on said pivot

15, the top portion 20 of the frame member 18 is placed in contact with the inner surface 17 of the band, and the friction between said member and band is sufficient for retaining 80 said member in any position into which it may be turned about said pivot. As illustrated in

Figs. 3 and 5, the members 14 are pivoted at substantially the mid-portions thereof to the band 13 and extend partially beyond the opposite end of said band.

In using the member 11 for keeping the hair off the sides of the face, the device is first manipulated for passing the combs 19 through the hair on each side of the face. In doing so, the side hair which passes through the teeth 24 is clamped to said teeth by the resilient lower portions of the frame members 18. The members 14 may thereafter be swung or pivoted inwardly to draw the hair off the face and tightly clamp the hair at the back of the head as shown in Fig. 1. It will be noted that the band 13 acts as a tension member for anchoring at its end portions 15 of the hair clamps 14.

The hair piece 12 for giving the effect of a long hair coiffure to a bobbed head having the side hair drawn in as described above, comprises a tuft of hair 30 of any construction for simulating the hair of the wearer. Means is provided for mounting said tuft 30 on the barrette portion 11. To this end a corrugated strip 31 is secured to the inner surface 11 of the band 13 as by gluing the contacting edges 32 of said member 31 to said band at the inner surface thereof, or in any other suitable manner. Said tuft 30 is formed with a binding edge 33, to which the hairs of said tuft are attached, and which may be sewed on the corrugated strip 31 by passing the thread 35 through said binding edge, then up through a space 36 between the strip 31 and the inner surface 17 of the band, then over the top edge of said strip and then down through the adjoining space 36. The thread is then again passed through the binding edge and up the adjoining space 36. This sewing operation is repeated along the entire length of the strip. Due to the corrugations of strip 31, the band 13 may be bent without breaking the former.

In using an appliance 10 having a hair piece 12, the clamping members 18 may be swung underneath the tuft 30 which thereby partially hides said members from view. The tuft 30 thus simulates an extension of the hair that is drawn in from the sides of the face, and hence produces a highly desirable and good-looking coiffure for a bobbed head.

Fig. 7 illustrates a modified construction in which the hair clamping members 18^a are pivoted to the band 13^a at their inner end portions 19^a. With this construction, the members 18^a may extend further beyond the ends of the band for engaging the side hair. Furthermore, by simply turning said clamps 18^a, 180° from the position shown in Fig. 7, the effective length of the device may be adjusted. The main portion of the clamps will then extend inwardly of the ends of the band 13^a, thus considerably shortening the device. Since a longer device 10 may be necessary for use with short hair, and a shorter device is more effective for longer natural hair, the single device by the simple adjustment may serve for either the short or long hair.

As clearly shown in Fig. 6, the heads 15^a of

rivets 15 may be capped as at 15^b, preferably by moldable material similar to that of the band 13 and hair clamps 14, to enhance the appearance of the device. This is particularly desirable where the rivets are metallic, so that no metal parts will show. The capping material may be applied over the heads 15^a, in the fused state, said material thus adhering to the adjacent portions of the band and clamps.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A hair dressing appliance comprising a member adapted to fit the back of the neck and means associated with said member for drawing in and retaining the said hair off the face, said means comprising a hair clamping device pivoted to said member adjacent an end portion thereof, said clamping device including a comb and a resilient member associated therewith for clamping the hair to the comb.

2. In a barrette of the character described, a band, and hair clamping devices pivoted to the outer ends of said bands, each of said devices comprising a frame member and a comb having a portion fixed to a portion of said frame member.

3. A hair dressing appliance comprising a curved band adapted to fit the back of the neck and means associated with said band for drawing in and retaining the side hair off the face, said means comprising a pair of hair clamping devices pivoted to said band adjacent the end portions thereof, said devices comprising a comb and a resilient member for clamping the hair to the comb.

4. In a woman's hair dressing appliance, in combination with a curved band, a corrugated member secured to said band, and a tuft of hair attached to said corrugated member.

5. In a woman's hair dressing appliance, in combination, a curved band, a tuft of hair simulating human hair, provided with a binding edge portion and means for mounting said tuft on said band; said means comprising a corrugated strip secured to said band and stitching extending through said binding edge portion for sewing said portion to said corrugated member.

6. A hair dressing appliance comprising a member adapted to fit the back of the neck

and means associated with said member for drawing in and retaining the side hair off the face, said means being adjustable for varying the effective length of the appliance.

5 7. A hair dressing appliance comprising a member adapted to fit the back of the neck and means for drawing in and retaining the hair off the face, said means comprising a hair clamping device, a pin for pivotally mounting said device on said member, and a cap of 10 moldable material for covering an end portion of said pin.

In testimony whereof I affix my signature.

JESSE OPPENHEIM.
